UNITED STATES PATENT OFFICE.

JAMES M. WORTH, OF CHICAGO, ILLINOIS.

TRACTION MECHANISM.

1,209,370.

Specification of Letters Patent. Patented Dec. 19, 1916.

Application filed May 1, 1915. Serial No. 25,096.

To all whom it may concern:

Be it known that I, JAMES M. WORTH, a citizen of the United States, and resident of Chicago, in the county of Cook and State 5 of Illinois, have invented certain new and useful Improvements in Traction Mechanism, of which the following is a description, reference being had to the accompanying drawings, which form a part of my 10 specification.

My invention relates to traction mechanism more especially intended for use in connection with traction engines and the like, and has for its object the provision 15 of a tractor element so constructed that it will practically act as a rigid truss between the centers of the axles of the driving wheel and the driven wheel, thereby insuring positive traction.

Another object of my invention is to provide mechanism of the class specified which will be absolutely rigid between the driver and the driven wheels without the use of any intermediate permanent or stationary 25 supports and therefore without producing friction on the tractive mechanism; the construction being such, however, that it may readily flex, as it passes about the wheels beyond the centers of the axles, as will be 30 readily understood from the following detailed description.

In the drawings:—Figure 1 is a longitudinal sectional view of my improved mechanism. Fig. 2 is a vertical sectional view taken on the line 2—2 of Fig. 1, looking in the direction of the arrows. Fig. 3 is a vertical sectional view of one of the wheels, taken on the same line as Fig. 2, with the traction element removed. Fig. 4 is a detail plan view illustrating the method of forming the interlocking cleats or shoes of the mechanism. Fig. 5 is a side elevation and partial sectional view of a modified form of my invention. Fig. 6 is a sectional view taken on the line 6—6 of Fig. 5 to a point just beneath the center or axis. Fig. 7 is a detail plan view of the inner belt-portion of my mechanism illustrated in Fig. 5. Fig. 8 is a detail view of one of the 50 links, as employed in Figs. 5 and 6, shown in side elevation. Fig. 9 is a detail plan view of a modified form of the inner belt-portion.

In the particular exemplification of my invention as illustrated in the first three 55 figures of the drawings, I show two wheels 10 and 11, which are preferably similar in

construction except one of the wheels is intended to be the power or driving wheel, while the other is the driven wheel.

The wheel 10 is shown as the driver, and 60 is therefore provided with the gear 12, which is adapted to mesh with any suitable train of gearing driven by any suitable motive power. The axles of both wheels, of course, are mounted or journaled in suitable bearings in the usual manner, so that 65 illustration and description of the mountings and frame of the vehicle need not be entered into.

The wheels 10 and 11 are preferably constructed of two side disks 13 and 14, suitably spaced apart by means of the hub-portion 15, which is shown made integral therewith. Each side member or disk 13 and 14 is provided with a multiple or series 70 of flat surfaces 16, see Fig. 2. These surfaces are of a size commensurate with the width of the shoes or cleats hereinafter described, and the number of flat surfaces is determined both by the size of the wheels 75 and the width of the cleats or shoes of the tractor element.

In the construction illustrated, the sides or peripheries of the wheels are shown provided with flanges or rims 17, whereby 80 centering of the tractor element is insured.

The tractor element comprises a series of 85 shoes or cleats 18, preferably of cast steel. These cleats 18 are preferably formed with off-set sides as more clearly shown in Fig. 4, 90 so as to provide extended portions 19, of equal width, and spaced apart a distance slightly greater than the width of the extended portions. The extended portions 19 are arranged in a staggered manner on opposite sides of the cleat as shown in Fig. 4, 95 so that the portions 19 on one side of the shoe or cleat will be opposite to the indented portions or intervening spaces on the other side of the cleat. It is evident from the 100 construction just described, the extensions 19 on one side of a cleat will register with or dove-tail into the intervening spaces on one side of the adjacent cleat; the cleats being similarly constructed and therefore 105 interchangeable.

The ends of the extended portions 19 are 110 preferably shown made circular in cross-section and provided with registering holes to receive the connecting or hinge pins 20, which therefore extend transversely of the tractor element as shown in Figs. 1 and 2.

The shoes or cleats 18 are each provided with a pair of arms 21, 21, disposed at right angles to the tractive surfaces, see Figs. 1 and 2, so as to be presented inwardly. The 5 arms are formed on the under surface of the cleats at a point somewhat removed from the ends of the cleats, so as to permit both ends of the shoes or cleats 18 to overlap or come into contact with the flat surfaces 16 10 of the wheels, as shown in Fig. 2.

In order to provide greater strength, I prefer to unite the arms or right angularly disposed portions 21, of the cleats, by a web 22, see Fig. 2; the web being made arcuate 15 as shown so as to not interfere with the inner member or controlling element now to be described.

The inner ends of arms or portions 21 are pivotally connected at 23, to an endless member or element 24; the legs 21 being pivoted to opposite sides of the endless member (as shown in Fig. 2), so as to straddle the same. The connection between the legs 21 and the element 24 is made by short pivots or pins 25 so as not to interfere with the proper movement of the element about the hub 15 of the wheels. The links of chain or element 24 are united by the long pins 25 which extend from side to side of chain 24, as shown in 30 Fig. 2, and provide the pivotal or flexible points for the chain, as disclosed in Fig. 1, at the points where the element is passing about the hubs of both wheels 10 and 11. The chain 24 is so formed that the links will 35 straddle the circumferential rib or flange 26, formed centrally on the hubs of both wheels 10 and 11, see Fig. 2.

The traction belt or mechanism is made of a length just sufficient to extend about 40 the peripheries of both wheels, so that both the cleat or shoe-portion or element and the inner chain-portion or element of the mechanism will be held taut throughout the entire length thereof.

45 It is evident from the construction that as the tractor mechanism is revolved, the intermediate pivotal points of the inner element 24, formed by the pins 25, will be moved or pressed out by the circumferential rib or flange 26, at a point substantially in the same vertical plane as the axes of the wheels, thus inducing a proper flexing of the inner element 24 where it passes about the hubs of the wheels; the inner element, 50 however, remaining unflexed throughout its travel intermediate of the points where it contacts with the rib or engaging member 26.

In Fig. 5, I show, in side elevation, and 60 partially in section, a modified form of my improved traction mechanism, wherein the wheels 27 and 28 are provided with diverging sides or disk-portions, as more clearly shown in Fig. 6, so as to provide rim-portions or fellies separated by an intervening

space extending down to the hub-portion, as shown in Fig. 6; the rim-portions and hub being preferably formed integral as shown. The rims or fellies of the wheels 27 and 28 are provided with equidistant grooves 70 or notches, as shown at 29, see Fig. 5; the notches or grooves being spaced apart to correspond with the width of the cleats 18 of the outer element of the traction mechanism. The grooves or notches 29 are adapted to receive the dovetailed or interlocking extended portions 19 of adjacent cleats 18, 75 namely the extended portions of the cleats which receive the connecting or pivot pins 20. It is apparent from the construction shown and described that a good gripping relation between the wheels 27 and 28 and the outer traction element of the mechanism is provided, so that positive movement of the tractor portion of the mechanism is induced. 80 The surfaces of the peripheries of the wheels, intermediate of the notches or grooves 29, are made flat to correspond with the flat under surfaces of the cleats 18.

In the construction illustrated in Fig. 5, 90 each cleat 18 is shown provided with a tapering arm 21^a, see Fig. 6. The inner or free ends of the arms 21^a receive the pins 30 which pass transversely through the arms 21^a and also through the overlapping ends 95 of the links 31 of the inner element or belt of the mechanism; the links 31 being arranged intermediate of the free or inner ends of arms 21^a, as shown in Figs. 6 and 7. The links of the inner belt or element are 100 preferably of the construction more clearly shown in Figs. 7 and 8, namely with the flat sides as shown, being provided with an inner opening of sufficient size to allow the links to slide on the connecting pins 30 in 105 the manner shown in Fig. 5 at the points where the traction element of the mechanism moves or travels about the wheels 27 and 28, namely at points just beyond the vertical centers of the hubs of the wheels. 110

In Fig. 6, I show the drive wheel 27 provided with a suitable gear 32, whereby power is imparted to the wheel 27 and through it to the tractor element of the mechanism, thus causing said element to 115 rotate about wheel 28.

In Fig. 9, I show a modified form of the inner belt or element, wherein each alternate member or link-portion comprises two links 31^a, similar to links 31 shown in Figs. 120 7 and 8, arranged parallel and spaced apart by an intermediate link 31^b of somewhat greater width. The general construction of these links, however, is substantially similar to that shown in Figs. 7 and 8; the overlapping ends of the link-portions receiving the pins 30, as in the construction previously described. It is evident that with this construction, the traction element, at points intermediate of the vertical centers of the two 125 130

wheels 27 and 28, is rigidly held in its normal position, namely with the inner ends of the arms 21^a of the cleats held against movement beyond their maximum spaced relation as shown in Fig. 5 intermediate of the wheels. The inner element will prevent the traction element being pressed out of the horizontal plane shown, as the members or links 31 limit or prevent the inner 10 ends of the arms spreading. It will be understood, of course, that the traction element in this construction, like the traction element illustrated in the first three figures of the drawings, is made of a length just 15 sufficient to permit it to extend about the peripheries of the two wheels, so that the inner and outer elements of the mechanism will be held taut, thereby providing a rigid truss intermediate of the vertical centers 20 of the wheels, without the necessity of employing any stationary means, such as shoes and the like, for holding the tractor-element in proper position.

It is evident from the constructions shown 25 and described, that a positive and rigid tractor-belt or mechanism is provided which obviates the necessity of having frictional engagement with means for maintaining the proper operative position of the traction element. I am thus enabled to overcome the serious objections that have heretofore been 30 encountered in mechanisms of the nature herein described; at the same time providing mechanism which will possess proper flexibility at the points where it must move about 35 the axes of the wheels.

I have shown and described what I believe to be the best forms of my invention, but the same may be altered in certain respects without, however, departing from the 40 spirit of my invention, and I do not wish, therefore, to be understood as limiting myself to the exact constructions shown and described.

45 What I claim is:—

1. Traction mechanism, comprising a pair of wheels each having double peripheral portions spaced apart and provided with a plurality of flat-engaging surfaces, said peripheral portions being formed integral with a hub provided with a central flange, an 50 endless tractor element extending about the peripheral portions of the wheels and

adapted to span the intervening spaces, said element consisting of a plurality of cleats 55 having alternating extended sides and recesses, with the recesses of one cleat adapted to receive the extended portions or sides of an adjacent cleat, the extended portions being provided with registering holes to receive connecting pins, both ends of each cleat being provided with inwardly presented tapering arms or strut-braces disposed on opposite sides of the central flange on the hub of each wheel, an endless element or 60 truss adapted to move about the hubs of the wheels intermediate of the peripheral portions and pivotally connected with the inner ends of both arms of each cleat to prevent spreading movement of the arms or strut- 65 braces of adjacent cleats, said inner element being also provided with intermediate yielding points formed by transversely extending pins adapted to extend across said hub-flange and be engaged thereby so as to cause 70 said intermediate yielding points to move off "dead center" in a predetermined manner during travel of both elements about the wheels.

2. Traction mechanism, comprising a pair 80 of wheels, each composed of spaced disks or felly-portions which are provided with engaging surfaces, a tractor element composed of cleats having alternating extended sides and recesses, with the recesses of one 85 cleat adapted to receive the extended portions of an adjacent cleat, the extended portions being provided with registering holes to receive connecting pins, each cleat being provided with a pair of inwardly extending 90 tapering arms or strut-braces arranged so as to provide spaces intermediate of the inner ends of the arms of adjacent cleats, and an inner endless element pivotally secured between the ends of the pair of arms of each 95 cleat and arranged to maintain the arms of adjacent cleats against spreading beyond the maximum spaced relation, said element being arranged to permit movement of the arms or strut-braces of adjacent cleats toward each other during movement of the 100 tractor element about the wheels.
